UNITED STATES PATENT OFFICE.

FREDERICK HABENSACK, OF SAG HARBOR, NEW YORK.

DESIGN FOR A HANDLE FOR SPOONS OR FORKS.

SPECIFICATION forming part of Design No. 36,422, dated July 14, 1903.

Application filed April 15, 1903. Serial No. 152,804. Term of patent 3½ years.

To all whom it may concern:

Be it known that I, FREDERICK HABENSACK, a citizen of the United States, and a resident of Sag Harbor, in the county of Suffolk and State of New York, have invented a certain new, original, and ornamental Design for a Handle for Spoons or Forks, of which the following is a specification.

In the accompanying drawings, Figure 1 shows the obverse side of a handle of a spoon or fork having the design applied thereto, and Fig. 2 the reverse side.

What I claim is—

The ornamental design for a handle for spoons or forks, substantially as shown. 15

Signed at Sag Harbor, in the county of Suffolk and State of New York, this 13th day of March, A. D. 1903.

FRED. HABENSACK.
